UNITED STATES PATENT OFFICE.

DANIEL W. GUILES, OF TACOMA, WASHINGTON.

FLOOR-DRAIN.

1,117,036.

Specification of Letters Patent. Patented Nov. 10, 1914.

Application filed September 1, 1910. Serial No. 580,011.

To all whom it may concern:

Be it known that I, DANIEL W. GUILES, a citizen of the United States, residing at Tacoma, in the county of Pierce and State 5 of Washington, have invented new and useful Improvements in Floor-Drains, of which the following is a specification.

This invention relates to floor drains or traps.

10 The object of the invention is the provision of means for connecting the drain or trap with a waste pipe and a vent pipe so that the latter will occupy a small space in the basement or cellar of the house and 15 the waste pipe may be swung to either direction without altering the location of the trap.

For perfectly sanitary plumbing, it is an absolute necessity that a fixture be caused 20 to waste into floor drains or traps because otherwise the water in the trap would evaporate and permit sewer gas to enter the house.

It is the object of this invention to provide means whereby a fixture such as a laundry tub or the like may waste into the trap 25 so as to keep it properly primed.

Further objects of the invention will appear as the following specific description is 30 read in connection with the accompanying drawing which forms a part of this application, and in which:

Figure 1 is a side elevation. Fig. 2 is a vertical longitudinal section. Fig. 3 is a 35 top plan view.

Referring more particularly to the drawing 1 represents the hopper of the trap which is covered by a foraminous top 2 removably mounted thereon as is usual. The 40 lower end of the trap is bent into Y-shape as shown at 3 and the tail of the trap is provided with a threaded extension 4 upon which a T-coupling is threaded. The lateral internally threaded extension 6 of said 45 coupling is adapted to be connected to a waste pipe and the vertical internally threaded extension of the T-coupling is adapted to be connected to a vent pipe. It will therefore be seen that the coupling may

be turned around so as to present the lateral 50 extension for connection with a waste pipe in almost any direction. The opposite side of the hopper from the tail is bulged upon its side as shown at 8 and is provided with an internal boss 9 which is raised above the 55 top of the hopper and is internally threaded to receive a waste pipe from any fixture such as a laundry tub or the like. The boss is hollow or tubular throughout its length and opens directly into the hopper so that the 60 waste from the tub or other fixture will drain directly thereto and keep the trap properly primed. Both the extension 7 and the internal boss 9 are projected above the 65 top of the hopper 1 so that disconnection of the waste and vent pipes may be made without tearing up the floor.

Having thus described the invention, what is claimed is—

A device of the character described comprising a funnel-shaped receptacle, a waste pipe communicating with the bottom of said receptacle, and extending laterally therefrom, said waste pipe being formed with a returned portion disposed substantially parallel with the axis of said funnel-shaped receptacle, a T-coupling removably engaging said returned portion of said waste pipe, said T-coupling having its main axis disposed in line with said returned portion, a 70 perforated cap snugly fitting the open wide neck of said funnel-shaped receptacle, and a pipe having the greater part of its circumference disposed within the circumference of said funnel-shaped member, said 75 last named pipe having an arc of its circumference disposed in projecting relation with respect to the periphery of said funnel-shaped member and having its lower portion deflected inwardly whereby to have its 80 mouth disposed substantially in line with the stem of said T-coupling.

In testimony whereof I affix my signature in presence of two witnesses.

DANIEL W. GUILES.
